UNITED STATES PATENT OFFICE.

MICHAEL J. LARKIN, OF PAWTUCKET, RHODE ISLAND, ASSIGNOR TO RHODE ISLAND TEXTILE COMPANY, OF PAWTUCKET, RHODE ISLAND, A CORPORATION OF RHODE ISLAND.

BRAIDING MACHINE.

Application filed August 21, 1922. Serial No. 583,107.

To all whom it may concern:

Be it known that I, MICHAEL J. LARKIN, a citizen of the United States, residing at Pawtucket, in the county of Providence, State of Rhode Island, have invented certain new and useful Improvements in Braiding Machines, of which the following is a specification.

This invention relates to braiding-machines and consists particularly of an improved device for interweaving into the braid an additional strand or strands which may be of a distinguishing color to produce a border design at the selvage or stripes running through the length of the fabric.

One object of the invention is to provide a simplified mechanism of the class specified which may be applied to use as an attachment for braiders of standard type without alteration in the general arrangement or structure of the machine.

Another object of the invention is to provide a device which may be applied to the braider within the confines of its race-plate without requiring extension or enlargement thereof.

Another object of the invention is to provide a device which may be operated automatically from the carriers of the machine without requiring additional driving-elements, such as gears or the like.

Further objects of the improvement are set forth in the following specification which describes a preferred embodiment of the invention as illustrated in the accompanying drawings.

In the drawings:

Fig. 1 is a plan view of the race-plate of a common type of braiding-machine showing the bobbin-carriers in place thereon and illustrating my improved device applied to use therewith;

Fig. 2 is a vertical sectional view of a portion of the machine taken on the line 2—2 of Fig. 1 looking in the direction indicated by the arrow *a*;

Fig. 3 is a perspective view of the device detached from the machine;

Fig. 4 is a detailed view of the arrangement for mounting the device on the machine; and

Fig. 5 is an enlarged detailed view of a length of braid showing one style of selvage produced by the use of the improved attachment on a certain type of machine.

My improved device is designed for use with a well known type of braiding-machine embodying an undulatory raceway or track in which two series of bobbin-carriers move in opposite directions to intermesh the yarns or strands delivering therefrom. As shown in Figs. 1 and 2, the raceway for the carriers is formed in a circular top-plate 5 which is supported above and in parallel relation with the horizontal bottom-plate 6, see Fig. 65. The bottom-plate 6 is usually supported from legs or standards 7 and the top-plate 5 is held in spaced relation thereabove by means of shouldered studs 8 extending between the plates. Certain of the studs 8 are arranged around the outer rim of the plates 5 and 6, as shown in Fig. 1, while another set have their axes disposed in a circle at a distance inwardly from the rim. This second set of studs serves to support the quoits 70 which are of substantially circular shape in outline and disposed within the cut-out sections 11 of the race-plate 5. Through this well known form of construction the top-plate 5 is provided with a series of intersecting tracks or races 12 and 13 arranged in a generally concentric relation with respect to the axis of the machine. In the type of machine herein illustrated, which is adapted for producing a flat braid, the two intersecting races 12 and 13 are not continuous in a circumferential direction but have a gap 14 at a point between the two terminal quoits 15 and 16. That is to say, the races extend around the machine in loops which cross 80 each other at regular intervals except at one point where the end loops 17 and 18 are separated by the gap 14 where the races do not intersect. Through this arrangement the bobbin-carriers 20 which slide in the 85 races are caused to move around the machine in one direction to a certain point and to then move back again in the opposite direction.

The carriers 20 consist of shoes 21 slidable in the races or tracks 12 and 13 with their flanges 19 overhanging the edges of the race-plate 5 and its correlated quoits 10. Rising above the shoes or runners 21 are spindles 22 on which are mounted the usual yarn bobbins *b*. The bobbins *b* carry ratchet-disks *d* at the top whereby their rotation to unwind the yarn is controlled by pawls 23. The pawls 23 are slidable on standards 24 under the draft on the yarns *y* which lead up 100

through guide-eyes 28 at the top of the standards. This form of carrier is of a type generally used in the art but the arrangement of its tension and let-off mechanism 5 may be varied as desired.

Projecting below the shoes 21 of the carriers are lugs or horns 25 adapted to be engaged by radial slots 26 in the rims of the horn-gears 27 which are arranged beneath the quoits 10. Referring to Fig. 2, the horn-gears 27 are journaled on the studs 8 which extend between the centers of the quoits 10 and the bottom-plate 6, and the adjacent gears form a train arranged with 15 their teeth intermeshing as indicated by the dotted lines in Fig. 1. The several gears 27 in the train are driven from one of the end gears through the use of suitable driving means, not herein shown. Suffice it to state 20 that alternate gears in the train turn in opposite directions so that the carriers 20 are propelled along the races 12 and 13 by sliding them through the curved loops thereof while passing them from one gear to another in regular sequence. The carriers 20 are thus caused to traverse the race 12 in a clockwise direction with respect to the axis of the machine until they pass into the end loop 17, and continuing therearound 25 concentrically of the axis of the end gear are traversed back in the opposite direction through the race 13. As the carriers enter the opposite end loop 18 of the raceway they are swung therearound and passed back into 30 the race 12, and so on throughout the continuous operation of the machine. In this manner the carriers 20 are caused to move in a sinuous course whereby those moving in one direction will dodge those passing in 40 the opposite direction so that the strands *y* leading from one set of bobbins will be interlaced over and under the yarns from the other set to plait them into the braid.

The braiding-machine illustrated in Fig. 45 1 is constructed with a raceway composed of six loops with thirteen carriers traversing therein to produce a relatively narrow flat braid. The present braider, however, serves merely as one illustration of the method of 50 applying my improved device to use, and it is to be understood that the invention is adapted for other types of braiders having in some cases a greater or less number of carriers or with their arrangement modified in other respects. My improved device 55 may also be applied to the braider in a number of different ways to produce various patterns or color effects in the fabric, and I have preferred to herein illustrate the invention as adapted for interweaving the pattern or color strand into the edges of the fabric to form a fancy selvage. For this 60 purpose I employ two of the extra strand-inserting devices which are located at the 65 end loops of the raceway.

Referring to Fig. 3, my improved device or attachment is here illustrated in its simplest form as consisting of a plate or disk 30 adapted to rest on one of the quoits 10 of the race-plate 5 and carrying a supplemental supply-bobbin *c* for the the colored strand *x* to be woven or braided into the fabric. The bobbin *c* is mounted on a spindle 31 rising from a foot 32 secured to the top of the disk 30, the foot also carrying a standard 33. On the standard 33 is a sliding weight 34 controlled by the strand *x* to lift the pawl 35 free of the ratchet head *e* on the bobbin *c* to permit the latter to rotate to deliver its yarn *x*; the arrangement being 70 the same as that for the bobbin-carriers 20 previously described.

The disks or plates 30 are rotatively mounted on the quoits 10 coaxially of the horn-gears 27 and their journal studs 8. As 85 a convenient means for mounting the disks I may provide a vertical post or spindle 37 which has a threaded bore at its lower end to adapt it to screw onto the upper end of the stud 8 in place of the nut usually employed. The disk 30 is bored axially at 38, see Fig. 3, to adapt it to rotate on the post 37 and on its under side is a reduced boss 39 which rests against the top of the quoit 10, as shown in Fig. 4.

Projecting from the side of the disk 30 is an arm or lug 40 which extends across the raceway in the top-plate 5 in position to be engaged by the ends of the carriers 20 as they slide therein, see Fig. 1. Through this means the disk 30 is adapted to be rotated on its axis to revolve the bobbin *c* around the central post 37 in the manner and for the purpose as later explained. At the top of the post 37 is the usual selvage-bar 42 consisting of a tapering spindle or needle projecting radially inward and upward toward the axis of the machine with its tip at the braiding point where the strands *y* merge into the fabric *F*, see Fig. 2.

Having now described the construction and arrangement of my improved device in detail its method of operation will next be explained: With the type of braider herein illustrated the carriers 20 move back and forth around the axis of the machine in a tortuous course with the yarns *y* sinuating in and out to pass them alternately over and under each other. As the carriers reach the end loops 17 and 18 of the raceway they are revolved around the end quoits 10 and are thus brought into contact with the lugs 40 on the disks 30. Fig. 1 shows one of the carriers 20 after it has entered the end loop 18 of the raceway and engaged with the lug 40 on the disk 30. The carrier referred to moves in a clockwise direction in the loop 18 and consequently the disk 30 is rotated in the same direction as indicated by the arrows *f*. The turning of the disk 30 swings 95

the bobbin *c* around the post 37 and causes its strand *x* to be entwined or looped with the yarn *y* leading from the bobbin *b* on the carrier. That is to say, as the carrier 20 5 enters the end loop 18 of the raceway its yarn *y* will pass in under the yarn *x* from the bobbin *c*, but as the carrier passes out of the end loop its yarn *y* draws up over the top of the post 37 and is passed above or 10 over the yarn *x*, see Fig. 2. As shown in this latter view, the selvage-bar 42 acts as a guide for the yarns leading to the braiding point and serves to prevent the crossed yarns from snarling and tangling.

15 As one carrier passes out from the end loops of the raceway it leaves the lug 40 in position to be engaged by the next carrier entering thereinto. This action is illustrated at the opposite loop 17 in Fig. 1. Here the 20 carrier 20 is passing from the end loop 17 into the race 13 and the lug 40 has been carried beyond the crossing point of the raceway. It will be noted, further, that the end 25 of the lug is clear of the side of the shoe of the carrier, this being due to the momentum of the disk 30 which continues its rotation a slight distance beyond the point where the impulse of the carrier ceases.

It will be observed by reference to Fig. 1 30 that with the arrangement of the machine as herein shown only every other carrier will operate on the lug 40 of the disk 30 to swing the bobbin *c* around the post 37. That is to say, the extra strand *x* will be entwined or 35 looped by every other yarn *y* plaited into the selvage of the braid F, resulting in a fabric substantially as illustrated in Fig. 5. As here shown the braid is composed of thirteen 40 yarns *y* with two extra, colored strands *x* intermeshed therewith at the selvages; it being understood that two of the devices are 45 used for this purpose, one at each end loop of the raceway, as shown in Fig. 1. While this pattern in the selvage is practically uniform there will be, however, a slight break 50 in its continuity at certain intervals due to the odd number of carriers used. That is to say, the strand *x* will be looped under every other yarn for eleven picks, but at the twelfth pick it will be plaited under two 55 of the yarns *y* before continuing in regular sequence again. The colored yarns *x* produce a variegated pattern at the selvage of the braid to heighten the artistic effect, and various other patterns may be produced by 60 arranging the yarns in different combinations. Moreover, by employing more of the attachments at different locations in the raceway a greater number of colored strands 65 may be introduced into the fabric to produce a wider variety of patterns. For instance, the fabric may be braided with a series of colored stripes spaced at intervals of its width. Still more fanciful and intricate patterns are possible by applying the

attachment to use with braiders employing a larger number of carriers, and if desired the device might be arranged with a plurality of supplemental bobbins *c* mounted on each disk 30.

It will be observed from the foregoing that my invention provides an extremely simple mechanism for introducing extra strands into the fabric produced on the braiding machine. The device may be applied to the 70 braider without alteration or rearrangement of its operating mechanism and without machining or fitting of the parts. All that is required to attach the device to the braider is to remove the appropriate nut on the 75 quoit where the extra bobbin *c* is to be located and to replace it with the post 37 having the disk 30 rotatively mounted thereon. No extra gears or other driving-mechanism are required to operate the device as the disks 80 30 are rotated from the movement of the carriers 20 without the intervention of other parts. Furthermore, the attachment is applied to place within the confines of the raceplate of the machine without extending or 85 enlarging the same and without adding extra loops to the raceway. The mode of application of the device may be varied at will 90 to produce a wide variety of patterns and color effects in the fabric, the combinations 95 being only limited by the size and capacity of the machine.

It will also be observed that the simplicity of the device renders it economical to manufacture and proof against derangement, or 100 getting out of order.

Various modifications may be made in the form and structure of the device without departing from the spirit or scope of the invention; therefore, without limiting myself 105 to the exact embodiment herein shown and described, I claim:

1. In a braiding machine, the combination with a plurality of bobbins, of means to move the bobbins in opposite directions in sinuous courses to cause them to intermesh the strands delivering therefrom, a supplemental-bobbin mounted to revolve about an axis located between the opposite 110 courses of movement of the main bobbins, and means to revolve said supplemental-bobbin about said axis during the passage of a main bobbin whereby to intermesh the extra strand therefrom with the other strands of the fabric.

2. In a braiding machine, the combination with a plurality of bobbin-carriers, of means to move said carriers in opposite directions in sinuous courses to plait their 115 yarns into the braid, a supplemental-bobbin mounted to revolve in a circular orbit substantially concentric with a portion of the courses followed by the carriers, and means to revolve said supplemental-bobbin to cause 120 its strand to be looped around the yarns 125 130

1. delivering from the bobbins on the carriers to intermesh it therewith.
2. In a braiding machine, the combination with the race-plate thereof having a raceway comprising a series of intersecting loops, of bobbin-carriers adapted to slide in the raceway, means to propel the carriers through the loops of the raceway, means for mounting a supplemental-bobbin to adapt it to be revolved around the inside of a loop of the raceway, and means for revolving said supplemental-bobbin around the loop concurrently with the passage of a carrier therethrough.
3. In a braiding machine, the combination with a race-plate having a sinuous raceway comprising a series of intersecting loops, of bobbin-carriers slidable in the raceway, means to propel the carriers in opposite directions through the loops of the raceway, a supplemental-bobbin mounted to move in a circular course substantially concentric with a loop in the raceway, and means operated from the carriers to carry the supplemental-bobbin around its course to cause its strand to be plaited into the fabric.
4. In a braiding machine, the combination with a race-plate having a raceway comprising a series of intersecting loops, of bobbin-carriers adapted to slide in the raceway, means to propel the carriers in opposite directions in the raceway, means for mounting a supplemental-bobbin to adapt it to be revolved about an axis coincident with the center of a loop in the raceway, and means operated from a carrier as it moves around said loop to revolve the supplemental-bobbin to cause it to loop its strand around the yarn delivering from the bobbin on the carrier.
5. In a braiding machine, the combination with a race-plate having a raceway comprising a series of intersecting loops, of bobbin-carriers adapted to slide in the raceway, means to propel the carriers through the loops of the raceway, a pivoted bobbin-holder, a supplemental-bobbin mounted on said holder to adapt it to swing around the inside of a loop in the raceway, and means engageable by a carrier as it moves around said loop to rotate the bobbin-holder to loop the strand from the supplemental-bobbin around the strand delivering from the bobbin on the carrier.
6. In a braiding machine, the combination with a race-plate having a raceway comprising a series of intersecting loops, of bobbin-carriers adapted to slide in the raceway, means to propel the carriers through the loops of the raceway, a vertical post arranged at the center of a loop in the raceway, a savage-bar projecting from the top of the post toward the braiding-point of the machine, a disk rotatable on said post, a supplemental-bobbin carried by said disk, and a lug projecting from the disk across the raceway to adapt it to be engaged by a carrier to rotate the disk to swing the supplemental-bobbin around the loop.
7. In a braiding machine, the combination with a race-plate having a raceway comprising a series of intersecting loops with substantially circular quoits defining the inner edges thereof, of bobbin-carriers slidable in the raceway, means to propel the carriers through the loops of the raceway, a bobbin-holder rotatably mounted on the axis of a quoit, a supplemental-bobbin mounted on said holder in eccentric relation to the axis thereof, and means on said holder adapted to be engaged by a carrier as it moves around the quoit to cause the supplemental-bobbin to be revolved to loop its strand around the yarn delivering from the bobbin on the carrier.
8. In a braiding machine, the combination with a race-plate having a raceway comprising a series of intersecting loops, of bobbin-carriers slidable in said raceway, means for propelling the carriers in opposite directions through the loops of the raceway, a support rotatable on an axis at the center of a loop in the raceway, a supplemental-bobbin carried on said support in eccentric relation to the axis thereof, and means for rotating said support to swing the supplemental-bobbin around the loop concurrently with the passage of a carrier therethrough.
9. In a braiding machine, the combination with the race-plate thereof having a raceway comprising intersecting loops, of substantially circular quoits arranged within the loops of the raceway, bobbin-carriers slidable in the raceway, means to propel the carriers through the loops of the raceway, a plate pivoted on an axis located at the center of a quoit, a supplemental-bobbin supported on said plate in eccentric relation to the axis thereof, and means on the plate projecting across the raceway to adapt it to be engaged by a carrier to revolve the supplemental-bobbin around the inside of the loop of the raceway.
10. In a braiding machine, the combination with the race-plate having a raceway comprising intersecting loops, of bobbin-carriers slidable in said raceway, means to propel the carriers through the loops in the raceway, a vertical post arranged at the center of a loop in the raceway, a savage-bar projecting from the top of the post toward the braiding-point of the machine, a disk rotatable on said post, a supplemental-bobbin carried by said disk, and a lug projecting from the disk across the raceway to adapt it to be engaged by a carrier to rotate the disk to swing the supplemental-bobbin around the loop.

In testimony whereof I affix my signature.

MICHAEL J. LARKIN.
